UNITED STATES PATENT OFFICE

ANDREW EPPLER, OF LYNN, MASSACHUSETTS, ASSIGNOR TO UNITED SHOE MACHINERY CORPORATION, OF PATERSON, NEW JERSEY, A CORPORATION OF NEW JERSEY.

MACHINE FOR USE IN THE MANUFACTURE OF SHOES

Application filed December 29, 1930. Serial No. 505,297.

This invention relates to machines for use in the manufacture of shoes and the machine herein shown and described, for the purpose of illustrating one embodiment of the invention, is particularly designed for operating on shoes the uppers of which are provided with flanges to which soles may be secured.

Machines of the type disclosed in United States Letters Patent No. 1,720,212, granted July 9, 1929, on my application, are in successful use to secure together the sole-attaching flanges of uppers and the margins of soles, the sole-attaching flanges of the uppers or 15 the marginal portions of the soles or both having been previously coated with cement.

In the operation of machines of the type referred to, the upper is worked progressively over a last, the outturned sole-attaching flange of the upper being tucked into the angle between the side of the last and the projecting marginal portion of the sole and pressed against the sole to cause the upper and sole to adhere. In making certain types 25 of shoes, however, such for example as those made in accordance with the method disclosed in United States Letters Patent No. 1,230,954, granted June 26, 1917, on application of Charles Tweedie, it is desirable to secure the sole-attaching flange of the upper to the sole without the use of a last. Shoes of the type disclosed in the Letters Patent referred to just above are known in the trade 30 as "prewelted" shoes. The present invention, however, is not limited in its application to prewelted shoes but may be applied to any type of shoes wherein the uppers have sole-attaching flanges which act to secure the uppers to the soles.

An object of this invention, accordingly, is to provide a machine for pressing together a sole and an outwardly directed sole-attaching flange of an upper, in the operation of which the use of a last may be dispensed with, and particularly to provide a machine for 45 effecting adhesion between the welts and soles of prewelted shoes while off the last.

To this end one feature of the invention resides in a machine having a tool for progressively engaging successive portions of the

sole attaching flange of an upper, for example, a welt attached to an upper, a work support for engaging a shoe sole, means for forcing the upper toward the tool, and means for effecting relative movement between the tool and support to press the flange and sole together. In the illustrated machine a tool having an inclined edge for engaging the upper surface of a welt, a work support movable to press the sole against the welt, and a roll 55 mounted on a horn and engaging the inside of the shoe cooperate to effect progressively the attachment of the upper and sole of a prewelt shoe by cement.

Another feature of the invention consists 60 in a machine for operating on shoes provided with feeding means arranged to engage a portion of the work already operated upon and to feed the work to present a new portion thereof to the operating instrumentalities 65 of the machine. In the illustrated machine means is provided for gripping a portion of the work already operated upon, such as the projecting edge portion of the shoe, that is, the outer marginal portions of the 70 welt and sole, and means for moving said gripping means intermittently to feed the shoe past the operating instrumentalities. In the illustrated machine, the gripping means comprises a vertically fixed upper jaw 75 the lower face of which is parallel to that of the tool and a vertically movable lower jaw the sole-engaging face of which is parallel to the upper surface of the sole support. As 80 illustrated, the machine is so organized and operated that the jaws grip the shoe when the work support is lowered and are moved in the direction of feed, that is, in a plane parallel to the plane of the work-engaging faces 85 of the tool and support, to feed the work and present another portion of the work to the operating instrumentalities, during the operation of which the feed jaws are released and returned toward the operating instrumentalities in position to engage and feed the work again. In the illustrated machine, the feed jaws are normally closed by a spring, and the movement of the work support is utilized to move the jaws to feed the work, to 95 100

open them to release the work, and to return them to initial position.

Another feature of the invention is to provide means for preventing premature adhesion of the shoe parts. To this end the illustrated machine is provided with a separating blade which is located in advance of the tool and support and is normally located between the welt and sole to prevent premature adhesion between the surfaces. In the illustrated machine manually operated means is provided for introducing the blade into operative position and for withdrawing it when its use is not desired, as when the operation on a shoe has been nearly completed.

These and other features of the invention will appear more fully from the following description when read in connection with the accompanying drawings and will be pointed out in the appended claims.

In the drawings,

Fig. 1 is a view in side elevation of a machine embodying the present invention;

Fig. 2 is a front elevation of the machine;

Fig. 3 is an enlarged view of the head of the machine as shown in Fig. 1;

Fig. 4 is an enlarged view of the head of the machine as shown in Fig. 2; and

Fig. 5 is an enlarged detail view of the operating instrumentalities of the machine, showing in section a shoe being operated upon.

The drawings represent a machine for effecting progressively the attachment of the welt of a prewelt shoe and its sole by cement. The illustrated machine comprises a column 10 at the upper end of which is secured a bracket 12 which carries a lasting tool 14 having a work engaging face 16 (Fig. 5) inclined at 45 degrees to the vertical and having a beveled outer end adapted to enter the angle between the upper and welt of a prewelt shoe. The tool 14 carries on its work-engaging face a gage 18 which may be adjusted relatively to the beveled end of the tool 14. The gage 18 has sufficient extent heightwise of the shoe to engage the edge face of the sole, welt and a portion of the edge face of the sole, there being sufficient space between the gage 18 and the upper face of the work support so that the application of pressure by the work support to the sole and welt is not interfered with. The stem 13 of the tool 14 is arcuate and is received in a corresponding recess in the bracket 12. The stem 13 is clamped in adjusted position by a plate 15 and bolts 17 which pass through arcuate slots in the stem 13, through the plate 15 and through the bracket 12, and clamp these parts rigidly together.

A sole support 20 having its sole-receiving face inclined to correspond to the inclination of the tool 14 is provided with a split sleeve 22 which is secured by means of cap screws 24 to the upper end of a post 26. The

post 26 is arranged for vertical sliding movement in bearings 28, 30, in the upper one of which it is splined to prevent rotation. The post 26 carries a shock-absorbing collar 32 which will engage the bearing 28 before the surfaces of the gage 18 and support 20 come into contact, thus forming a stop to limit upward movement of the work support.

The machine is arranged for both manual and power operation. On each side of the post 26 is a roll 34 each of which is engaged by a cam surface 36 formed on a cam member 38. The member 38 is pivoted to the bearings 30 at 40 and has a rearwardly extending arm 42 to which a treadle rod 44 is pivoted at 46, the lower end of the rod 44 being pivoted to an inner treadle 48 at 50. The treadle rod 44 is held in raised position by a spring 51, in which position of the treadle rod the cam member is swung outwardly far enough not to apply upward pressure to the rolls. When the treadle 48 is depressed, the cam member 38 is swung in under the rolls 34 and acts to raise the rod 26 and causes the support 20 to approach the tool 14. When in this position the cam member 38 positively sustains the work and prevents separation of the work and the tool.

The tool 14 (Fig. 5) engages only a portion of the transverse extent of the welt and to press the remaining portion of the welt a roll 52 is provided which has a movement toward the tool 14 with a component of movement toward the support 20. The roll 52 is mounted on the lower end of a horn arm 53 for rotation on an axis perpendicular to the general plane of the shoe-sole-engaging surface of the support 20. The horn arm 53 is adjustably secured in the eye of an eye-bolt 54 the stem of which is journaled in a bearing 56 formed on one end of a shaft 58. The arm 53 rotates about the axis of the stem of the eye-bolt 54 which is substantially in alignment with the axis of the roll 52, and when the arm 53 is rotated the position of the roll 52 relatively to the tool 14 and the support 20 is not changed. The arm 53 is also mounted for rotation about an axis substantially parallel to the sole-engaging surface of the support 20. To this end the shaft 58 is journaled in a bearing 60 which extends perpendicular to the axis formed by the stem of the eye-bolt 54 and is formed in a part of a swinging frame 62. The rear end of the shaft 58 has pinned thereto a stop member 64 having a slot which is engaged by a member 65 secured to an arm 66 on a latch 68 to prevent the lateral swinging movement of the horn arm 53 and the roll 52. The latch 68 is pivoted to the frame 62 at 70 and is normally held in operative position by a spring 72. If it is necessary for any reason to swing the horn arm laterally, it is only necessary to press an arm 74 of the latch toward the frame a sufficient distance to throw the latch 65 out

of the slot in the stop member 64 and permit lateral swinging movement of the horn arm 53. The stop member 64 is also provided with two projecting lugs which engage the member 65 to limit the lateral swinging movement of the horn 53. From the above description it is apparent that the horn 53 can be swung laterally of the sole support 20 about an axis parallel to the sole-engaging face of the support to permit a shoe to be put on or taken off of the horn and that the horn may be rotated about an axis perpendicular to the sole-engaging surface of the support to permit the operator to feed the shoe to the lasting tool and support without interference from the curved horn.

The roll 52 is moved toward both the tool 14 and the support 20 by mechanism which will now be described. The frame 62 carrying the roll 52 and the horn 53 is pivoted at 78 to an upwardly and outwardly extending arm 76 secured to the bracket 12 of the machine which permits the frame 62 carrying the roll 52 and the horn 53 to be swung toward and away from the tool 14 and the support 20. The frame 62 is caused to swing toward the members 14 and 20 by means of appropriate connections to the driving mechanism of the machine. The frame 62 has an extension arm 80 which carries in a hole at its free end a pin 82, the pin being securely held in place by means of a set screw 84. The rear end of the pin 82 is provided with a hole through which passes a rod 85 carrying at its upper end a collar 86 engaging the pin 82.

The lower end of the rod 85 is enlarged and slides in a bearing 87 which forms a part of the bracket 12. A spring 88 surrounds the smaller portion of the rod 85 and engages the collar 86 at its upper end. The tension on the spring 88 is adjusted by means of a nut 89 which determines the pressure to be applied to the upper and welt by the roll 52. The lower end of the rod 85 bears against the head of a stud 91 which is threaded into an extension 92 formed on the split sleeve 22. The frame 62 is returned to its normal position by the action of a spring 93 secured to the pin 82 and to the machine frame. The extension arm 80 is provided with an adjustable stop screw 94 which contacts with the arm 76 to limit the return movement of the frame 62.

A separator blade 95 is mounted adjacent to the tool 24 and the support 20 to prevent premature adhesion between the welt and the sole prior to the operation of pressing the welt and sole together. The blade 95 is mounted for sliding movement in the bracket 12 in such a manner that the blade is free to move in a plane vertical to the sole-engaging surface of the support 20. A pin 96 is secured to the upper end of the blade 95 and extends through a slot 97 cut in the plate 15. The

separator blade is yieldingly held toward the support 20 by means of a plug which is pressed against the upper surface of the plate by a spring 99 and by another plug which is urged toward the blade by means of a spring 101, said plug engaging either one of two shallow recesses in the blade to hold it yieldingly in either its operative or inoperative position. The fact that the separator blade 95 is loosely mounted and is urged toward the sole-engaging surface of the support 20 by means of the springs 99 and 101 permits the blade to move with the support and thus prevents the blade from pulling apart the portions of the shoe which have been previously cemented together. A bell-crank lever 98 is pivoted at 100 to the extension arm 76, and the lever 98 is provided at its lower end with a slot through which the pin 96 passes. When it is desired for any reason to remove the blade 95 from its position shown in Fig. 3, it is only necessary to pull the upper arm of the lever 98 to the left (Fig. 3) and the blade will be moved toward the right out of the path of feed of the shoe.

For feeding the work intermittently past the tool 14 and the support 20, feeding jaws 102, 104 are provided. The jaw 102 has a shank portion 106 (Fig. 3) the lower end of which is secured by means of screws 108 to the back of a slideway 110. The slideway 110 is pivoted at 112 (Fig. 4) to the machine column. The lower jaw 104 is secured to a slide 114 by a cap screw 116. The lower end of the slide 114 is forked for the reception of a spring 118 which normally urges the slide 114 and the jaw 104 upwardly toward the jaw 102. The upward movement of the jaw 104 is controlled by a pawl-and-ratchet mechanism which is operated between feeding movements of the feed mechanism to force the jaw 104 downwardly away from the upper jaw.

A pawl-carrying arm 120 is pivotally mounted on the bearing 28 at 122. The free end of the pawl-carrying arm 120 has pivoted thereto at 119 a pawl 123 which has teeth on its lower end for engaging teeth on the lower end of the slide 114, the teeth being so formed that when the arm is depressed the slide 114 will be pushed down. The arm 120 also carries a retaining pawl 125 which is also pivoted to the arm 120 at 119 and has teeth in its lower end for engaging teeth formed in the side of the lower portion 120 of the lower slideway 110, the teeth on the pawl and slideway being formed to permit downward movement of the pawl and arm and prevent upward movement thereof. The pawl 125 is normally urged toward the slideway 110 by a spring 121 which is located in recesses formed in the arm 120 and in the pawl 125, and a similar spring similarly arranged urges the pawl 123 toward the teeth in the slide 114. When permitted to do so,

the spring 121 causes the pawl 125 to engage the teeth on the slideway 110 and the similar spring causes the pawl 123 to engage the teeth on the lower end of the slide. When the teeth of the pawl 125 engage the teeth in the slideway 110, the arm 120 is prevented from moving upwardly under the influence of a spring 127 but may be moved downwardly. An adjustable stop member 129 is secured to an outwardly extending lug on the bearing 28 and limits the upward movements of the arm 120 under the influence of the spring 127.

The pivoted slideway 110 is provided with an outwardly extending arm 124 (Fig. 4) to which is pivoted a rod 126. Up-and-down movements of the arm 124 cause the slideway 110 to be swung about its pivot 112 to approach and recede from the tool 14 and support 20. The lower end of the rod 126 is pivotally connected to an arm of a bell-crank lever 128 (Fig. 2) which is pivoted to a projecting portion of a bearing 31 in which a plunger 131 reciprocates to operate the post 26 through connections to be described hereinafter. The other arm of the bell-crank lever is provided with a curved cam slot 130 which forms a cam path for a roll secured to an arm 132 which is pinned to the post 131. As the post 131 is reciprocated in the power operation of the machine, the roll on the arm 132 moves in the cam slot 130, which is shaped to impart through the bell-crank lever 128 the required up-and-down movements to the rod 126. The upper end of the rod 126 has secured thereto a member 134 which carries an adjustable stop screw 135 arranged to contact at appropriate times with the lower surface of both pawls 123 and 125. The arm 124 is provided with an adjustable stop screw 136 which contacts with the upper surface of the pawl-carrying arm 120.

When the rod 126 is moved downwardly by the mechanism described, the stop member 136 on the arm 124 is moved toward the upper surface of the pawl-carrying arm 120 and during this interval the feed jaws 102, 104 are swung to the left. Further downward movement of the arm 124 causes the adjustable stop member 136 to engage the upper surface of the pawl-carrying arm 120, swinging it downwardly so that the pawl 123, already released by the stop screw 135 and in engagement with the teeth on the slide 114, moves the slide downwardly and releases the lower jaw against the tension of the spring 118. At the same time the pawl 125 is released and its teeth slide past the teeth on the slideway 110 and prevent upward movement of the arm 120 during the first portion of the upward movement of the rod 126. When this upward movement of the rod 126 occurs, the stop member 135 does not immediately engage the lower surface of the pawl 125 because the adjustable stop 135 is then spaced from the

pawl. This first movement, however, serves to rock the slideway 110 on its pivot 112 and carry the jaws 102, 104 back to their position adjacent to the support 114 and the tool 20. Further upward movement of the rod 126 causes the stop 134 to engage the lower surface of the pawl 125 and release its teeth from the slideway 110, permitting the arm 120 to be lifted against the stop 129 by the spring 127. At the same time the stop 135 engages the pawl 123 and releases it from the slide 114, thus permitting the jaw 104 to be forced upwardly under the influence of the spring 118. The feeding jaws 102, 104 are thus operated automatically to clamp and feed the work, and after each feeding movement the jaws are returned to substantially their original position before the lower jaw is released to permit it again to clamp the work.

It is to be understood that since the shoe is made without a last, an upper *a* is cut by a suitable pattern to the exact size required for the shoe, a welt *b* of uniform width being sewed by stitches *c* to the edge of the upper with the edge of the upper and one edge of the welt flush with each other. A sole *d* is cut to the proper final shape and preferably a filler *e* is attached to the sole, the filler being of the same shape as the sole but smaller so that a uniform margin of the sole will be exposed about the periphery of the filler, the width of the margin being the same as that of the welt. This exposed margin is coated with cement, such as latex, as is also the lower face *g* of the welt.

The upper and its welt are placed over the horn 53 with the inner surface of the upper adjacent to the welt in contact with the roll 52. The sole prepared as described is placed on the support 20 under the upper and the upper and sole properly located with respect to each other. The shoe is positioned with the welt under the tool 14 with its edge and the edge of the sole abutting against the gage 18; then, by operation of the treadle 48, the support 20 is moved toward the tool 14 and presses the sole against the welt.

The roll 52 forces the upper against the tool 14 and the gage 18 to cause the edge of the welt and the edge of the sole to be brought into alignment with each other. In this way the tool 14, support 20 and roll 52 co-operate to position the shoe parts and to press the welt against the projecting portion of the sole, the cemented surfaces being thus caused to adhere. This manual operation of the machine is of advantage during the preliminary stages of the operation to enable the upper to be located relatively to the sole.

To continue this manual operation to complete the securing of the shoe parts would, however, be very slow and fatiguing to the operator. With the present organization the operator can shift from manual operation to power operation of the machine by de-

pressing a treadle 150. This treadle 150 fulcrumed at 151 (Fig. 1) is held raised by a spring. A rod 153, connected at one end to the treadle 150, is yieldingly connected at its upper end by a spring 152 to one arm of a bell-crank lever 155. A rod 157 connects the other arm of the bell crank to a detent 156 pivoted between ears formed on the lower end of the vertical shaft 131. By depression of the treadle 150 the detent 156 is swung over a continuously power-operated plunger 154. At its lower end the plunger 154 is pivoted to an eccentric strap mounted on an eccentric 158 (Fig. 2). The eccentric is secured to a shaft 160 which carries connections to a source of power such as an electric motor 162.

The vertical shaft 131 has a reduced upper portion which enters a bore in the lower end of the post 26. Surrounding the upper end of the reduced portion of the shaft 131 is a sleeve having an enlarged lower end 164 which rests on a spring 166. This spring surrounds the reduced portion of the shaft 131 and rests at its lower end in a cup-like member 168 surrounding the shaft 131. The spring 166 presses at its upper end on the enlarged lower end of the sleeve 164 which is held on the upper end of the reduced portion of the shaft 131 by a pin which passes through the shaft and through slots in the sleeve. The lower edge of the cup 168 rests on the member 132 and contact of the lower surface of the member 132 with the bearing 31 limits downward movement of the shaft 131 in such position that the detent 156 will swing over the plunger 154 when the plunger is in its lowest position.

When the treadle 150 is depressed, the plunger 154 will engage the detent 156 and force upwardly the shaft 131, the upper end of the reduced portion of the shaft will move in the bore in the lower end of the post 26 until the sleeve 164 engages the post, whereupon the post will be raised by the sleeve and, if the movement of the sleeve is arrested, the spring 166 will be compressed. If there is work between the tool and support, a greater compression of the spring will occur. When the cam 38 is in its outward position, a full upward stroke will be given to the support 20 at each operation of the eccentric. If desired, the operator may depress the treadle 48 to raise the support 20 by the cam 38 to reduce the stroke of the support while the machine is power-operated. The connections between the post 26 and the plunger 158 are the same as those described in my prior patent referred to above to which reference may be had for a more detailed description.

Although the parts of the machine have been described in detail, it may be well to refer briefly to the operation of the machine. The shoe parts are placed in the machine, and the machine is manually operated as described

above to locate properly the prewelted upper relatively to the sole. In continuing the operation on the shoe by power, the treadle 150 is depressed, causing the detent 156 to move into the path of movement of the continuously driven plunger 154, thus connecting the power means to the post 26 through vertical shaft 162. The eccentric 158, through the above-mentioned connections, causes the work support 20 to be moved upwardly to clamp the welt or sole-attaching flange of the upper to the welt. When the support 20 is moved downwardly, the feeding jaws 102, 104 engage the work and feed it to the left, as viewed in Fig. 2. At the end of the feeding movement, the lower feeding jaw 104 is moved downwardly by means of the pawl 123 on the pawl-carrying arm 120 and the stop 136 to release clamping pressure on the work. Thus, when the eccentric, through the connections, again moves the work support 20 upwardly to clamp the work, the feeding jaws are caused to move toward the tool 14 and the support 20 and, when the jaws have nearly completed their return movement toward the tool, the stop 134 will contact with the lower surface of the pawl 123, throwing the teeth on the pawl out of engagement with the teeth on the slide 114 which permits the jaw to clamp the work under the impulse of the spring 118. This completes one cycle of operation of the machine which will be continued as long as the treadle 150 is depressed. When the operation has nearly been completed, the separator blade 95 is moved out of engagement with the sole and welt by swinging the handle of the bell-crank lever 128 to the left, as viewed in Figs. 1 and 3, thus preventing the separating blade from pulling apart the portions of the shoe which have previously been cemented together.

It will be noted that the operation of the power means for moving the shoe support has no effect on the manual means for moving the support, these means being quite independent of each other as will be apparent from the detailed description in the above-mentioned Letters Patent No. 1,720,212.

Although the illustrated machine has been shown and described as operating on a prewelted shoe, it is apparent that the machine is not limited in its application to such a shoe but may be used to operate on shoes of any other type wherein the upper is secured to the sole by a sole-attaching flange.

Having thus described my invention, what I claim as new and desire to secure by Letters Patent of the United States is:—

1. In a machine for progressively effecting attachment of successive portions of shoe uppers to soles by cement, the combination of a member for engaging a sole-attaching flange of an upper, a sole support, means for forcing the upper toward the member, and means

- for relatively operating the member and support to press the flange and sole together.
2. In a machine for progressively effecting attachment of successive portions of shoe uppers to soles by cement, an edge gage for engaging the edge of a welt of the upper, a sole support, and means moving the upper relatively to the gage to force the upper toward the gage.
3. In a machine for progressively effecting attachment of successive portions of shoe uppers to soles by cement, the combination of a member for engaging a sole-attaching flange of an upper, a sole support, means engaging the upper, means for relatively operating the member and support to press the flange and sole together, and means for relatively operating the flange-engaging member and the upper engaging means to cause the upper to be forced against the member.
4. In a machine for progressively effecting the attachment of shoe uppers to soles by cement, the combination of means for engaging a sole-attaching flange of an upper, a work support for pressing the shoe sole against the sole-attaching flange, means for forcing the upper of the shoe being operated upon toward the tool, and means for effecting relative movement between the tool and work support to press the sole-attaching flange and sole together.
5. In a machine for progressively effecting attachment of shoe uppers to soles by cement, the combination of a tool for engagement, a sole-attaching flange of the upper, a work support movable relatively to the tool for causing adhesion between the flange and the margin of a sole, and means movable toward the tool for forcing the upper toward the tool.
6. In a machine for progressively effecting attachment of shoe uppers to soles by cement, the combination of a tool for engaging a sole-attaching flange of the upper, a work support movable relatively to the tool for causing adhesion between the flange and the margin of a sole, means engaging inside the upper opposite to the location of said tool, and means operated by the work support for forcing the upper-engaging means toward the tool.
7. In a machine for progressively effecting the attachment of shoe uppers to soles by cement, a tool for engaging a sole-attaching flange of the upper, a movable work support for pressing the projecting portion of a shoe sole against the sole-attaching flange to cause the parts to adhere, and means constructed and arranged to operate inside of a shoe to force the upper toward the tool.
8. In a machine for assembling the parts of pre-welt shoe, a tool having a welt-engaging surface, a work support having a surface for engaging a sole of a shoe, said welt and sole-engaging surfaces being parallel to each other, and means for forcing the upper of the shoe toward the tool.
9. In a machine for assembling the parts of shoes, a tool for engaging the outturned flange of a shoe upper, a work support mounted for movement toward the tool, and angularly movable means for forcing the upper toward the tool.
10. In a machine for assembling the parts of pre-welt shoes, a tool having a welt-engaging surface, a work support for engaging a sole of a shoe, a roll for engaging the inside of the shoe, and means for relatively moving the tool, support and roll to effect attachment of the welt to the sole.
11. In a machine for securing shoe uppers to soles, a tool having an inclined edge for engaging the upper surface of a welt, a support movable to press the sole against the welt, and a roll mounted on a horn and engaging the inside of the shoe to force the upper toward the tool to effect the attachment of the upper and sole by cement.
12. In a machine for attaching shoe uppers to soles by cement, a tool for engaging the sole-attaching flange of an upper, a support having a sole-engaging surface, said tool and support being movable relatively to each other to press the sole-attaching flange and sole to cause adhesion of the parts, and means constructed and arranged to engage the inside of the shoe to force the upper toward the tool and to press a portion of the sole-attaching flange against the sole.
13. In a machine for attaching pre-welted uppers to soles, a tool having a welt-engaging surface and a beveled outer end adapted to enter the angle between the upper and welt, a sole support having a sole-engaging surface parallel to the welt-engaging surface of the tool, means for relatively operating the tool and support to press the welt and sole together, and a roll adapted to engage the inside of the shoe adjacent to the welt to force the upper toward the tool.
14. In a machine for attaching shoe uppers to soles, a tool and support arranged for relative movement for pressing a sole-attaching flange of an upper to a sole, a horn arranged for relative movement to the tool, and a roll on the horn adapted to engage the inside of the upper adjacent to the sole-attaching flange, said roll acting to force the upper toward the tool.
15. In a machine for assembling the parts of pre-welt shoes, a tool having a welt-engaging surface, a work support having a surface for engaging a sole of a shoe, means for relatively moving the tool and support to press the welt and sole together, and a roll for engaging the inside of the shoe, said roll being mounted on a horn and arranged for movement relatively to the tool and support to force the upper toward the tool.
16. In a machine for attaching shoe uppers

to soles, a tool for engaging a sole-attaching flange of an upper, a support for engaging a sole, means for relatively moving the tool and support, a horn arranged for movement relatively to the tool and support, and a roll on the horn adapted to engage the inside of the upper adjacent to the sole-attaching flange of the upper to effect relative movement between the upper and the tool to force the upper against the tool.

17. In a machine for effecting the attachment of pre-weltd shoe uppers to soles by cement, a tool having a welt-engaging surface and a beveled end adapted to enter the angle between the upper and the welt, a sole support, means for relatively operating the tool and support to press the welt and sole together, a roll constructed and arranged to engage the inside of the shoe adjacent to the welt, and power means for moving the roll toward the tool to force the upper toward the tool.

18. In a machine for attaching pre-weltd uppers to soles by cement, a support having a sole-engaging surface, a tool for engaging a portion of the transverse extent of a welt, a roll adapted to engage the inside of a pre-weltd upper adjacent to the welt, and means for moving the support and roll toward the tool to press the welt and sole.

19. In a machine for attaching pre-weltd uppers to soles by cement, a tool adapted to enter the angle between the upper and welt to engage a portion of the transverse extent of the welt, a roll for engaging the inside of the upper adjacent to the welt, a sole support movable relatively to the tool to press the sole and welt together, and means for moving the roll toward the tool and support, said roll and tool acting to resist over substantially the entire transverse extent of the welt the pressure applied thereto by movement of the support.

20. In a machine for attaching pre-weltd uppers to soles by cement, a tool adapted to engage a portion of the transverse extent of the welt of a pre-weltd upper, a sole support movable toward the tool to apply pressure to a sole and the welt, and a roll engaging the inside of the upper adjacent to the welt, said tool and roll acting over substantially the entire transverse extent of the welt to resist the pressure of the support.

21. In a machine for attaching shoe uppers to soles by cement, a tool having a welt-engaging surface, a gage mounted on the tool for engaging the edge of a welt, a sole support movable toward the tool to apply pressure to a sole and welt to cause adhesion between them, and means for engaging the inside of the upper of the shoe, said means having a movement toward the tool to force the edge of the welt against the gage.

22. In a machine for attaching shoe uppers to soles by cement, a tool having a welt-en-

gaging face, a gage mounted on the welt-engaging face of the tool and having a height-wise extent sufficient to engage the edge of the welt and the edge of the sole, means engaging the inside of an upper adjacent to the welt to force the sole and upper against the sole and welt against the gage, and a sole support movable relatively to the tool to press the sole and welt together.

23. In a machine for attaching shoe uppers to soles by cement, a tool having a welt-engaging face, a gage mounted on the welt-engaging face of the tool and having a height-wise extent sufficient to engage the edge of a welt and a portion of the edge of a sole, means engaging the inside of an upper adjacent to the welt to force the sole and welt against the gage, and a sole support movable relatively to the tool to press the sole and welt together.

24. In a machine for attaching shoe uppers to soles by cement, means for securing a sole-attaching flange of an upper to a sole by adhesion of cement-coated surfaces of the flange and sole, and means for engaging a secured portion of the sole-attaching flange and sole to feed the shoe past the securing means.

25. In a machine for attaching shoe uppers to soles by cement, means for pressing a sole-attaching flange of an upper to a shoe sole to cause the flange and sole to adhere, and means for feeding the upper and sole past the securing means, said feeding means being constructed and arranged to engage a portion of the flange and sole already secured together.

26. In a machine for attaching shoe uppers to soles by cement, means for engaging the sole-attaching flange of a shoe upper, a support for a shoe sole arranged for movement toward the means for engaging the flange to press a sole against the sole-attaching flange of the upper to cause the parts to adhere, and means engaging a portion of the shoe for feeding the shoe past the pressing means.

27. In a machine for operating on pre-welt shoes, a tool having a welt-engaging surface, a movable work support having a sole-engaging surface for pressing the sole and welt together, and feeding means constructed and arranged to engage a portion of the shoe to feed the work past the tool and support.

28. In a machine for attaching the uppers of pre-welt shoes to soles by cement, a tool having a welt-engaging surface, a vertically movable work support for engaging a sole of a shoe, said tool and support operating to cause adhesion between the welt and the sole, and means engaging the welt and sole to feed the work past the tool and the support.

29. In a machine for attaching shoe uppers to soles by cement, a movable work support having a sole-engaging surface, a tool having a welt-engaging surface for pressing a sole

and a welt to cause adhesion of the welt and the sole, and feeding means constructed and arranged to engage the welt and sole to feed the work past the tool and support.

30. In a machine for attaching shoe uppers to soles, means for adhesively securing an upper to a sole, and means for engaging a shoe to feed the shoe past the securing means, said feeding means comprising a lower feed jaw and an upper feed jaw movable relatively to the lower jaw, both of said jaws being constructed and arranged to move toward and away from the securing means to impart a step-by-step movement to the shoe.

31. In a machine for attaching shoe uppers to soles, a tool for engaging a portion of a shoe upper, a work support movable relatively to the tool, means for forcing the upper of the shoe toward the tool, and means for feeding the work past the tool and the work support.

32. In a machine for operating on pre-welted shoes, a tool having a welt-engaging surface, a work support having a sole-engaging surface, a member mounted for angular movement toward the tool and the support and constructed and arranged to engage the inside of the shoe, and means for feeding the work past said tool, support and said member.

33. In a machine for attaching shoe uppers to soles by cement, means for attaching a sole-attaching flange of an upper to a sole by adhesion of cement-coated surfaces of the flange and sole, and a pair of feed jaws for engaging a secured portion of a sole-attaching flange and sole to feed the shoe past the securing means, said feeding jaws being constructed and arranged to clamp the work prior to the operation of the securing means.

34. In a machine for attaching shoe uppers to soles, a tool for engaging a sole-attaching flange of an upper, a support for engaging a sole, means for relatively moving the tool and support between work receiving and operating positions, a pair of feed jaws, said feed jaws being movable toward each other to clamp the work at substantially the end of the relative movement of the tool and support to operating position and movable away from each other at substantially the end of the relative movement of the tool and support to work receiving position for releasing clamping pressure on the work.

35. In a machine for attaching shoe uppers to soles, a tool for engaging the surface of a sole-attaching flange of an upper, a support for engaging a sole, means for moving the support between work receiving and operating positions, and means including a pair of feed jaws for feeding the shoe past the tool and support, said jaws being relatively movable to clamp the shoe at substantially the end of the movement of the support to

operating position and to release the shoe when the support is substantially at the end of its movement to work receiving position.

36. In a machine for attaching shoe uppers to soles, a tool for engaging the surface of a sole-attaching flange of an upper, a support for engaging a sole, means for moving the support between work receiving and operating positions, and means including a pair of feed jaws for feeding the work past the tool and support, said jaws being movable relatively to the tool and support to feed the work during movement of the support to work receiving position and to return the jaws to their original position during movement of the support to operating position.

37. In a machine for attaching shoe uppers to soles, a tool for engaging the sole-attaching flange of an upper, a support for engaging a sole, means for relatively moving the tool and support between work receiving and operating positions, an upper feed jaw, a lower feed jaw, means for relatively moving the jaws, and means for moving the jaws relatively to the tool and support to feed the work.

38. In a machine for attaching shoe uppers to soles by cement, means for attaching a sole-attaching flange of an upper to a sole by adhesion of cement-coated surfaces of the flange and sole, and a pair of feed members for engaging a secured portion of the sole-attaching flange and sole, said members comprising an upper jaw and a lower jaw, the lower jaw being movable away from the upper jaw at the end of the feeding movement of the feed jaws to release the work and movable toward the upper jaw at the end of the return movement of the feed jaws to clamp the work.

39. In a machine for attaching pre-welted uppers to soles, a tool having a welt-engaging surface and a beveled end adapted to enter the angle between the upper and welt, a sole support having a sole-engaging surface parallel to the welt-engaging surface of the tool, means for relatively operating the tool and support to press the welt and sole together, a roll adapted to engage the inside of the shoe adjacent to the welt to force the upper toward the tool, and means for engaging a portion of the shoe already operated upon to feed the shoe past the tool and support.

40. In a machine for effecting the attachment of pre-welted shoe uppers to soles by cement, a tool having a welt-engaging surface and a beveled end adapted to enter the angle between the upper and the welt, a sole support, means for relatively operating the tool and support to press the welt and sole together, a roll constructed and arranged to engage the inside of the shoe adjacent to the welt, power means for moving the roll to-

ward the tool to force the upper toward the tool, and a pair of feed jaws constructed and arranged to engage a portion of the shoe already operated upon to feed the work past the tool and support, said jaws also acting to clamp the sole and welt to cause the sole and welt to be held together more securely.

41. In a machine for attaching pre-welted uppers to soles by cement, a tool adapted to enter the angle between the upper and welt and to engage a portion of the transverse extent of the welt, a roll for engaging the inside of the upper adjacent to the welt, a sole support movable relatively to the tool to press the sole and welt together, means for moving the roll toward the tool and support, said roll and tool acting to resist the pressure over substantially the entire transverse extent of the welt applied thereto by movement of the support, and a pair of feed jaws for engaging a pressed portion of the welt and sole to feed the shoe past the tool and support.

42. In a machine for attaching pre-welted uppers to soles by cement, a tool adapted to engage a portion of the transverse extent of the welt of a pre-welted upper, a sole support movable toward the tool to apply pressure to a sole and the welt, a roll engaging the inside of the upper adjacent to the welt, said tool and roll acting to resist the pressure of the support over substantially the entire transverse extent of the welt, and means for feeding the work past the tool and support and for clamping the parts already operated upon to cause them to adhere more firmly.

43. In a machine for operating on shoes, a tool for engaging a portion of the welt of a pre-welted shoe, a work support movable relatively to the tool for pressing a sole against the portion of the welt, and means located adjacent to the tool and the work support to prevent adhesion between cemented surfaces of the shoe parts prior to the operation of the tool and support.

44. In a machine for operating on shoe parts, means for causing adhesion between the cemented surfaces of shoe parts, and means for preventing adhesion of the cemented surfaces prior to the operation of the first-mentioned means, said last-mentioned means being constructed and arranged for movement into inoperative position at the will of the operator.

45. In a machine for attaching shoe uppers to soles, a tool, said uppers and soles having cemented surfaces, a movable work support, a roll for engaging the inside of the shoe to force the upper of the shoe toward the lasting tool, and means located adjacent to the tool and the support to prevent adhesion of the parts of the shoe prior to the operation of the tool and support.

46. In a machine for operating on pre-welt shoes, a tool having a welt-engaging surface, a work support having a sole-engaging sur-

face, means for engaging the inside of the shoe to force the upper toward the lasting tool, means for feeding the work past the lasting tool, and means for preventing adhesion between the welt and the sole prior to the operation of the tool and support. 70

47. In a machine for operating on pre-welt shoes, a tool having a surface for engaging the upper surface of a welt, a work support having a sole-engaging surface constructed and arranged for movement toward the tool, a roll for engaging the inside of a shoe, said roll being constructed and arranged for angular movement toward the tool and support, and a separator blade mounted for movement into and out of the path of feed of the work, said blade when in operative position being adapted to prevent adhesion between the cemented welt and the sole prior to the operation of the tool and support. 75 80 85

48. In a machine for operating on pre-welt shoes, a tool having a welt-engaging surface, a gage on the tool, a work support having a sole-engaging surface parallel to the welt-engaging surface of the tool and movable toward the tool, and a roll mounted on a horn for engaging the inside of a shoe adjacent to the welt, said roll having a movement toward the tool for forcing the upper toward the tool and a movement toward the work support to press the welt against the projecting portion of the sole to cause cemented portions of the welt and sole to adhere. 90 95

49. In a machine for operating on pre-welt shoes, a tool, a work support movable relatively to the tool and having an outward and downward inclination to enable the operator to see the welt as the operation progresses, means for moving the support, and a roll having a positive connection with the means for moving the shoe support to cause the roll to be moved about an axis parallel to the surface of the sole support thereby causing the roll to have a component of movement toward the tool to force the upper toward the tool and a component of movement toward the support to press a portion of the welt and sole together to cause adhesion between cemented portions of the sole and the welt. 100 105 110

In testimony whereof I have signed my name to this specification. 115

ANDREW EPPLER.
